UNITED STATES PATENT OFFICE

MELLEN C. M. HATCH, OF BOSTON, MASSACHUSETTS, ASSIGNOR TO THE STANDARD STOKER COMPANY, INCORPORATED, A CORPORATION OF DELAWARE

LOCOMOTIVE

Application filed November 6, 1928. Serial No. 317,620.

The invention relates to locomotives provided with mechanical stokers, its objects being to strengthen the locomotive, to provide improved means for the introduction of the fuel by power and for convenience in hand firing, and to secure other objects which will be pointed out in connection with the description.

A preferred embodiment of the invention is 10 hereinafter described and is illustrated in the accompanying drawings in which

Fig. 1 is a detail, central, longitudinal, vertical section of the rear end of the locomotive and the forward end of the tender;

Fig. 2 is a detail view of the same parts, partly in plan and partly in plan section on the line 2—2 of Fig. 1;

Fig. 3 is a detail on the line 3—3 of Fig. 1; and

Fig. 4 is a detail view in perspective of a portion of the foundation ring of a locomotive boiler and an integral arch formed thereon for enclosing the fuel feed openings.

The frames of the locomotive and tender 25 are shown conventionally at 10 and 11. The backhead of the boiler of the locomotive is shown at 12; the firebox thereof at 13; the grates are indicated at 14; the cab firing floor or deck, at 15; and the tender deck at 16.

The walls of the boiler including its backhead which enclose the firebox, are, as usual, hollow and are bounded at the bottom by a foundation or mud ring 17. As usual, the foundation ring may be formed of a heavy casting or forging, and in carrying out the present invention, it is provided with an integral upstanding arch 18 which encloses the opening for the admission of fuel and to

which the inner and outer sheets 19, 20 of the backhead may be secured by usual means, without deviating from the common form, except that they are suitably cut away to provide a single fuel admission opening, the lower portion of which is devoted to the mechanical stoker and the upper portion, to hand firing. The upper portion of this opening is covered by a plate 21 having an aperture 22 in its upper portion for hand firing, 50 which aperture will in practice be covered by

an openable door (not shown) of any suitable form.

The space below the plate 21 and above the foundation ring is open for the accommodation of the stoker conduit and the admission of air for cooling the same. The opening in the backhead may be increased in the vertical dimension, without carrying it too high for convenient hand firing by off-setting the foundation ring downwardly across its bottom as indicated at 24, see Figures 3 and 4.

The rear portion of the fuel conduit may be of any preferred form, being shown as comprising a trough 25 located below the floor of the tender and receiving fuel from an aperture therein and being provided with a conveyor screw 26 and a suitable crushing device 23 cooperating therewith. Leading from the forward end of the trough 25 is a tubular conduit comprising a rearward section 27 universally jointed to the forward end of the trough 25 and the forward section 28 loosely telescopically fitting upon the rearward section and provided at its forward end with one element of a ball joint 29. The forward portion of the conduit comprises two freely telescoping sections 30, 31, the former having at its rearward end an element 32 of a ball joint which engages the element 29 and is seated upon and rigidly attached to a chair 33 carried by a frame member as 10 of the locomotive frame. The section 31 extends through the lower portion of the aperture in the backhead which is enclosed by the arch 18 and within the firebox takes the form of an upwardly opening elbow or nozzle 34 from which fuel is delivered into the firebox.

This elbow is seated upon and rigidly secured to a chair 35 attached to the portion 24 of the foundation ring which spans the lower end of the arch 18. A section 36 of the screw conveyor is located within the intermediate section of the conduit comprising the elements 27, 28, and a third section 37 is located within the conduit sections 30, 31 terminating at the base of the elbow 34. The three conveyor screw sections are united by universal joints and the whole is driven from a suitable motor, conventionally shown at 38, by means

of a shaft 39 connected with the rear end of the conveyor screw in any well known manner. The elbow 34 is protected from the furnace heat by a grated skirt 40 extending from its upper end to the firebox grate. The portion of the fuel conduit which is carried by the locomotive is preferably D-shaped, being flattened at the top, for the purpose of checking the tendency of the fuel to rotate and to jam at the elbow.

10 Fuel issuing from the elbow or nozzle 34 is scattered over the firebox grate by steam blasts issuing from a box 41 located immediately above the opening of the elbow and at its rearward side, and supplied with steam through a plurality of pipes 42 leading from a steam chest 43 secured to the outer sheet of the backhead and which may be connected as by means of a pipe 44 directly with the steam dome of the locomotive.

15 Each of the pipes 42 is preferably provided with an individual controlling valve as indicated at 45 whereby the trimming of the fire may be facilitated by cutting off the pipes leading to the box 41 which scatter the fuel over portions of the grate which may have been overfed with fuel.

20 The described arrangement for the admission of fuel through a common opening in the backhead facilitates the attachment of the steam pipes associated with the fuel distributor without requiring them to be extended downwardly under the foundation ring in accordance with the present practice in connection with stokers of the scatter feed type.

25 One of the serious difficulties encountered in mechanically firing a locomotive through its backhead is due to the expansion of the boiler under the influence of the furnace heat, this expansion moving the backhead backwardly a considerable distance, putting the stoker conduit under severe strain and sometimes causing its fracture or distortion. This difficulty is overcome in the construction above described by forming the portion of the conduit which is carried by the locomotive in two freely telescoping sections, each being rigidly and independently secured to the locomotive.

30 The invention is applicable both to new and old locomotives, the latter being easily remodeled for its incorporation. In old locomotives to which the invention is applied, it may sometimes be found desirable to put in an entirely new foundation ring or the arch 35 may be welded on to the existing foundation ring.

35 While the construction shown and described is highly efficient and desirable, the invention may be differently embodied within its scope as defined by the appended claims.

I claim:

1. A locomotive having a boiler including a firebox, a foundation ring bounding the lower margins of the walls of the firebox, such

ring having an integral upstanding arch portion, said portion and ring entirely bounding a fuel admission opening in the backhead of the firebox.

2. A boiler including a firebox, a foundation ring shaped to correspond to the ground plan of the firebox, the backhead of said firebox having a fuel admission opening therein, and said ring having an extended portion entirely bounding said opening.

75 3. As a new article of manufacture, a locomotive foundation ring shaped to correspond to the ground plan of a firebox, said ring having an integral upstanding arch formed in its rear transverse section, said arch and said rear transverse section entirely bounding an opening adapted to provide access for mechanical and manual firing of fuel to the firebox.

4. As a new article of manufacture, a firebox foundation ring having an upstanding portion with a fuel admission opening formed therethrough, said ring together with its upstanding portion entirely bounding said admission opening.

80 5. As a new article of manufacture, a boiler foundation ring having a portion with a firing opening of a boiler formed therein said portion entirely bounding said opening.

90 6. As a new article of manufacture, a boiler foundation ring comprising four side sections, said ring having an upstanding arch portion formed on one of said sections, said arch extending above said ring section a height sufficient to provide an opening therethrough for mechanical and manual firing of fuel to a boiler, said arch portion together with said ring section on which it is formed entirely bounding said opening.

95 7. As a new article of manufacture, the rearward transverse section of a boiler foundation ring having formed centrally thereof an upwardly extended portion entirely bounding and forming an archway adapted to form the firing opening of a boiler.

100 8. As a new article of manufacture, a boiler foundation ring having formed with one of its sections an extended portion entirely bounding and forming an opening in said ring adapted to form a firing opening of a boiler.

105 9. In combination, a boiler including a firebox having hollow walls, a foundation ring bounding the lower margins of said walls, said ring formed with an extended portion entirely bounding and forming a fuel admission opening into said firebox, and a stoker conduit positioned in said opening and mounted on said ring.

110 10. In combination, a boiler including a firebox having hollow walls, a foundation ring bounding the lower margins of said walls, said ring formed with an upstanding extended portion entirely bounding and

115 120 125 130

forming an elongated fuel admission opening through the firebox backwall, a firing floor extending rearwardly from such backwall and disposed in a horizontal plane intermediate the lower and upper margins of said opening, said floor arranged with said opening to permit hand firing of fuel through the opening above the floor, and a stoker conduit positioned in said opening and mounted on 10 said ring.

11. In combination, a boiler including a firebox having hollow walls, a foundation ring bounding the lower margins of said walls, the backwall of said firebox having a 15 fuel admission opening extending upwardly from its lower margin, a firing floor extending rearwardly from the firebox backwall and disposed in a horizontal plane intermediate the lower margin of said back- 20 wall and the upper margin of the opening therein whereby fuel may be introduced manually above said floor and mechanically from below said floor through such admission opening, and an upstanding extension of said 25 ring bounding said admission opening above and below said floor.

In testimony whereof I affix my signature.
MELLEN C. M. HATCH.
